CLAIM

The ornamental design for a rotisserie motor housing, substantially as shown and described.

DESCRIPTION

FIG. 1 is a front perspective view of the rotisserie motor housing showing my ornamental design;

FIG. 2 is a side elevation view thereof;

FIG. 3 is a front elevation view thereof;

FIG. 4 is a back elevation view thereof;

FIG. 5 is a bottom plan view thereof;

FIG. 6 is a top plan view thereof; and,

FIG. 7 is a fragmentary section view taken along line 7 of FIG. 1.

The electrical cord has been shown fragmentarily in FIGS. 1, 3, 4, 5 and 6 for convenience of illustration.
